Franz P. Kober

UNITED STATES PATENT OFFICE.

FRANK P. KOBERT, OF AMITYVILLE, NEW YORK, ASSIGNOR TO KOBERT MACHINE COMPANY, INC., OF NEW YORK, N. Y., A CORPORATION OF NEW YORK.

PROCESS AND APPARATUS FOR WORKING METALS.

1,398,028.

Specification of Letters Patent.

Patented Nov. 22, 1921.

Application filed September 29, 1917, Serial No. 193,906. Renewed February 24, 1921. Serial No. 447,554.

To all whom it may concern:

Be it known that I, FRANK P. KOBERT, a citizen of the United States, and residing at Amityville, in the county of Suffolk and State of New York, have invented certain new and useful Improvements in the Process and Apparatus for Working Metals, of which the following is a specification, such as will enable those skilled in the art to 10 which it appertains to make and use the same.

This invention relates to metal working machines such as heating, re-heating, riveting and welding machines, and my invention 15 consists in the introduction of an electric apparatus whereby a new apparatus or machine is produced, and a new method or process of operation performed in the working or fashioning of metal, and the object 20 of my invention is to provide a simple, practical and efficient process and apparatus for accomplishing the desired result.

In the accompanying drawing, I have shown for illustration a riveting machine of 25 pneumatic, hydraulic or similar type provided with an electric heating apparatus of simple construction and operation whereby a rivet blank may be electrically heated prior to its fashioning or heading by the 30 heading or plunger die.

The invention is fully disclosed in the following specification, of which the accompanying drawing forms a part, in which the separate parts of my improvement are 35 designated by suitable reference characters in each of the views, and in which:—

Figure 1. is a side view of my improved apparatus with part of the construction in section;

Fig. 2 is a partial section on the line 2—2 of Fig. 1 on an enlarged scale and with parts in a different position.

Fig. 3 is a sectional plan view of a contact casing which I employ;

Fig. 4 is a view similar to Fig. 1, but showing a modification; and,

Fig. 5 is a partial section on the line 5—5 of Fig. 4 on an enlarged scale and with parts in a different position.

In Figs. 1 to 3, inclusive, I have indicated at 11, the frame of the machine which is U-shaped in form and comprises a back member 12, a top arm 13 and bottom arm 14 said arms being provided at their ends with

heads 15 and 16 respectively. Mounted in 55 the head 15 and vertically movable therein, is a plunger die 17, connected with a plunger not shown, and connected with the plunger is a toggle construction 18, composed of toggle levers pivoted to a 60 toggle socket at 19, said socket being provided with a lever 20, connected with a piston rod 21, which is pivoted in a piston movable longitudinally of an air cylinder 22, said piston being not shown. 65 The cylinder 22 is provided with the usual controlling valve 23 provided with an air supply pipe 24 and a hand operated controlling rod or lever 25.

The toggle construction and the means 70 for operating the same, consisting of the air cylinder 22 and the parts connected therewith, is the same as usually employed in machines of this class, and it will be understood that any construction of this class 75 may be used for the purpose herein set out.

Mounted in the arm 14 is a stationary work piece supporting die 26, the top of which is provided with a recess 27, and mounted on the shank portion of said die 80 above the arm 14 is a magnetic coil 28, placed in connection with any suitable source of electrical supply by wires 29.

Supported at one side of the frame 11, centrally of the back portion thereof, is an electrical transformer 30, provided with leads or conducting members 31 and 32, and connected with the free end of the lead 31 is a contact casing 33, shown in section in Fig. 3, and a supplemental cylinder 34 is adjustably suspended from the head 15, as shown at 35, and a piston 36 is movable longitudinally thereof, and said piston is provided with a piston rod 37, to the lower end of which is connected an electrode 38, with 95 which the contact casing 33 is connected, as clearly indicated in Figs. 1, 2 and 3 of the drawing. The cylinder 34 is provided with a suitable valve 39, having a controlling rod or lever 40, and an air supply pipe 41 is connected with said valve and with the air supply pipe 24 of the cylinder 20, said air supply pipes 24 and 41 being in communication with a compressed air tank not shown. 100

Connected with the free end of the lead 105 32 is a cylindrical electrode 42 connected with the head 16 of the arm 14 as shown at 43, the top face of said electrode being pro-

vided with a recess 44 adapted to receive the head end of a rivet blank 45 passed through an aperture in the plates 46 to be riveted together.

5 Connected with the cylindrical electrode 42 is a water supply device 47, having an intake pipe 48 and exhaust pipe 49, whereby water may be circulated through the said electrode to cool same, and the pipe 49 is 10 coiled around the lead 32 to cool same, as shown at 50, and connected with the transformer as shown at 51. Connected with the contact casing 33 is a water supply pipe 52, and exhaust pipe 53, the pipe 53 being adapted to coil around the lead 31 to cool the same, as shown at 54, and connected with the transformer 30, as shown at 55. The transformer 30 is provided with a water discharge pipe 56, and said 20 transformer is adapted to be placed in connection with any source of electrical supply by wires 57.

The frame 11, with the parts connected therewith, as shown, is adapted to be suspended from a crane not shown, by means of a bale 58, with which a hook 59 connects, said hook being suspended from said crane by chains in the usual manner, and in suspending the machine in this manner, the 30 same may be moved along the work piece or plates 46, as shown, to heat rivet blanks in the usual manner, but it will be understood that the machine may be rigidly connected with a floor or bedplate and the work piece 35 moved therethrough, as is customary in various types of machines of the class to which this invention relates.

From the foregoing description, the operation will be readily understood on the consideration of the accompanying drawing and the following statement:—The normal position of the machine is that shown in Fig. 1 in which a rivet blank 45 is shown passed through the plates 46 and supported or 45 mounted in the recess 44, in the top of the electrode 42, and the electrode 38 is in its raised position. The electrode 38 is first moved into contact with the protruding end of the rivet blank 45 by manipulating the 50 lever 40 to admit air into the cylinder 34, which moves the piston 36 downwardly, and the electrode 38 connected therewith, into the position shown in Fig. 2, and held in such position until the blank 45 is heated to the 55 desired extent, after which the air supply to the cylinder 34 is shut off to permit the movement of the piston 36 and electrode 38 back into the position shown in Fig. 1, after which the machine is moved longitudinally 60 of the work to bring the heated blank into position between the dies 17 and 26, in which operation the heated rivet blank may be held against displacement by grasping the same with prongs or in any other desired manner, 65 and when the head of the rivet blank is in

the recess 27, the plunger die 17 is moved into engagement with the protruding end of said blank by operating the lever 25 to admit air into the cylinder 22 which operates the toggle construction 18 to depress said die 70 in the usual manner, and the result of this operation is indicated in full lines in Fig. 2, where the protruding end of the rivet blank is shown headed.

By means of the magnetic coil 28, the die 75 26 is magnetized and serves to hold the plates 46, and rivet blank in firm contact with said die in the operation of heading said rivet as hereinbefore described.

In the construction shown in Figs. 4 and 5 80 I have indicated a hand operated electrode 60, which is substituted for the electrode 38, and which is connected with the free end of the lead 31 by means of a contact casing 61, with which the water supply and discharge 85 pipes 52 and 53 are connected, and a lever device 62 is pivoted to the arm 13 at 63, and provided with oppositely directed arms 64 and 65, the arm 64 being connected with the contact casing 61 as shown at 66, and a 90 weight 67 is connected with the end portion of the arm 65. The arm 64 is provided adjacent to the end thereof, with a handle member, whereby the electrode 60 may be depressed against the action of the weight 95 67, to bring it in contact with rivet blank 45 as will be readily understood.

The construction shown in Figs. 4 and 5 shows a hand operated electrode which is substituted for the pneumatically operated 100 electrode 38, as will be readily understood, but the operation of the machine as shown in Figs. 4 and 5 will be exactly the same as that shown in Figs. 1 and 2 thereof, as will be 105 readily understood.

With my improvement, a work piece may be heated to the desired extent by electrodes brought in contact therewith, pneumatically or otherwise, and then fashioned by dies brought into alignment therewith, or said 110 work piece may be moved when heated into position between forming dies, as will be readily understood, and while I have shown certain details of construction for accomplishing the desired result, it will be understood that my invention is not limited to the 115 various combinations and arrangement of parts hereinbefore shown and described, and changes therein and modifications thereof, may be made within the scope of the appended claims without departing from the spirit of my invention or sacrificing its advantages.

The steps of the process herein described, which consists in supporting a work piece in 125 the form of a rivet blank on one electrode, moving another electrode into contact with said blank to heat the same, and then fashioning said heated blank by forming dies brought into alignment therewith, produce 130

a simple and very efficient method of operation and form a perfect rivet but it will be understood that my invention is not limited to the process of heating and heading rivet blanks as the process herein described may be used for the purpose of working metal generally speaking, as will be readily understood.

Having fully described my invention what I claim as new and desire to secure by Letters Patent, is:—

1. The method of working metal, which consists in suitably supporting a work piece in one electrode, moving another electrode into contact with said work piece to close the circuit between said electrodes to heat said work piece, moving said heated work piece onto a stationary die, and fashioning said work piece by a plunger die movable toward and from said stationary die.

2. The method of riveting a plurality of parts together, which consists in passing a rivet blank through an aperture in said parts, supporting the head end of said rivet blank in an electrode, moving another electrode into contact with the protruding end of said rivet blank to heat said blank, moving a supporting die into position to support said heated rivet blank, and moving a plunger die toward the heated blank supported by said first named die to head the same.

3. The method of riveting a plurality of parts together, which consists in passing a rivet blank through an aperture in said parts, supporting the head end of said rivet blank in an electrode, moving another electrode into contact with the protruding end of said rivet blank to heat said blank moving a supporting die into position to support said heated rivet blank and said parts, magnetically holding said blank and parts in firm contact with said die, and moving a plunger die toward the heated blank supported by said first named die to head the same.

4. The method of riveting a plurality of parts together, which consists in passing a rivet blank through an aperture in said parts, electrically heating said rivet blank by electrodes brought into contact therewith, moving forming dies into operative position with said heated blank and heading said heated rivet blank by the operation of one of said dies toward the other.

5. The combination with a machine of the class described having a pneumatically operated plunger die, of an electric heating apparatus independent of said die, and adapted to heat a work piece prior to its fashioning by said plunger die.

6. The combination with a machine of the class described having a pneumatically operated plunger die, of an electric heating apparatus independent of said die, and com-

prising a pneumatically operated electrode, adapted to heat a work piece prior to its fashioning by said plunger die.

7. In a machine for heating metals electrically prior to shaping the same, the combination with a plunger die and work piece supporting die of a stationary and a movable electrode, mounted at one side of said dies, said stationary electrode being adapted to support a work piece, and means for moving said movable electrode in contact with the work piece supported in said stationary electrode to heat the same.

8. In a machine for heating metals electrically prior to shaping the same, the combination with a plunger die and work piece supporting die, of a stationary and a movable electrode, mounted at one side of said dies, said stationary electrode being adapted to support a work piece, means for moving said movable electrode in contact with the work piece supported in said stationary electrode to heat the same, and means for bringing said dies into alinement with said heated work piece, and means for operating said plunger die to fashion said work piece.

9. The method of riveting a plurality of parts together which consists in passing the rivet blank through said parts, heating said rivet blank by passing an electric current therethrough, moving a supporting die and plunger die into alinement with said heated rivet blank and operating said plunger die to head said rivet blank.

10. The method of riveting a plurality of parts together, which consists in passing a rivet blank through said parts, supporting the head end of said rivet blank in an electrode, heating said rivet blank by a pneumatically operated electrode brought into contact with the rivet blank supported in said electrode, and heading said rivet blank by a pneumatically operated plunger.

11. In a machine of the class described, a frame, a stationary die and a plunger die mounted in said frame, spaced electrodes mounted on one side of the frame, and adapted to heat a work piece supported therebetween, means for moving the machine to bring said dies into alinement with said heated work piece, and means for operating said plunger die to fashion said work piece.

12. In a machine of the class described, a frame, a plunger mounted therein, a plunger die in operative connection with said plunger, a stationary die mounted in said frame, an electric transformer mounted at one side of the frame and provided with leads with the ends of which are connected electrodes, one of said electrodes being adapted to support a work piece, and means for moving the other electrode into contact with the work piece in said first named electrode to heat the same.

13. In a machine of the class described, a frame, a plunger mounted therein, a plunger die in operative connection with said plunger, a stationary die mounted in said frame, an electric transformer mounted at one side of the frame and provided with leads with the ends of which are connected electrodes, one of said electrodes being adapted to support a work piece, means for moving the other electrode into contact with the work piece in said first named electrode to heat the same, and means for cooling said electrodes.
14. In a machine of the class described, a frame, a stationary die and a plunger die mounted in said frame, spaced electrodes mounted on one side of the frame, and adapted to heat a work piece supported therebetween, means for moving the machine to bring said dies into alinement with said heated work piece, means for operating said plunger die to fashion said work piece, and means for cooling said electrodes and said transformer.
15. In a machine of the class described, a stationary electrode adapted to support a work piece, a pneumatically operated electrode movable toward and from the work piece supported in said stationary electrode to heat the same, and a pneumatically operated plunger die adapted to be brought into contact with said heated work piece to fashion the same.
16. In a machine of the class described, a stationary electrode adapted to support a work piece, a pneumatically operated electrode movable toward and from the work piece supported in said stationary electrode to heat the same, a stationary die and a plunger die, means for bringing said dies into alinement with said heated work piece and means for operating said plunger die to fashion said heated work piece.
17. In a machine of the class described, a stationary die and a plunger die, a stationary electrode and a movable electrode mounted at one side of said dies, pneumatic means for operating said movable electrode to heat a work piece supported in said stationary electrode, means for bringing said dies into alinement with said heated work piece and pneumatic means for operating said plunger die to fashion said heated work piece.
18. In a machine of the class described for riveting a plurality of parts together by rivet blanks passed therethrough, a stationary electrode adapted to support a rivet blank, a pneumatically operated electrode movable toward and from said rivet blank and adapted to heat the same, and means independent of said electrodes for fashioning said heated rivet blank.
19. In a machine of the class described for riveting a plurality of parts together by rivet blanks passed therethrough, a stationary electrode adapted to support a rivet blank, a pneumatically operated electrode movable toward and from said rivet blank and adapted to heat the same, a stationary die and a plunger die, means for moving said dies into alinement with said heated rivet blank and pneumatic means for operating said plunger die to head said heated rivet blank.
20. In a machine of the class described, a stationary electrode adapted to support a work piece and an electrode movable toward and from said stationary electrode and adapted to heat the work piece supported therein, and means independent of both said electrodes for fashioning said heated work piece.
21. The method of riveting a plurality of parts together, which consists in passing a rivet blank through said parts, heating said rivet blank by passing an electric current therethrough, magnetically supporting said blank and parts, and moving a plunger die toward and from said rivet blank to head the same.
22. The method of riveting a plurality of parts together, which consists in passing a rivet blank through said parts, heating said rivet blank by passing an electric current therethrough, bringing a stationary die and plunger die into alinement with said heated rivet blank, magnetically holding said rivet blank in firm contact with said parts, and operating said plunger die to head said heated rivet blank.
23. The method of riveting a plurality of parts together, which consists in passing a rivet blank through said parts, supporting said rivet blank in a stationary die, magnetically holding said rivet blank in firm contact with said parts, and heading said rivet blank by a plunger die movable toward and from the same.
- In testimony that I claim the foregoing as my invention I have signed my name in presence of the subscribing witnesses this 25th day of Sept., 1917.
